Primary Examiner — Clare E Heflin(74) *Attorney, Agent, or Firm* — Renner, Otto, Boisselle & Sklar, LLP(57) **CLAIM**

The ornamental design for a luminaire, as shown and described.

DESCRIPTION

FIG. 1 is a bottom perspective view of a luminaire, showing a first variant of the design;

FIG. 2 is a front view thereof;

FIG. 3 is a side view thereof;

FIG. 4 is a bottom view thereof;

FIG. 5 is a top view thereof;

FIG. 6 is a top perspective view thereof;

FIG. 7 is a bottom perspective view of a luminaire showing a second variant of the design;

FIG. 8 is a front view thereof;

FIG. 9 is a side view thereof;

FIG. 10 is a bottom view thereof;

FIG. 11 is a top view thereof; and,

FIG. 12 is a top perspective view thereof.

The portions of the luminaire shown in broken lines form no part of the design. The thin diagonal lines indicate translucency.

1 Claim, 2 Drawing Sheets(56)
